UNITED STATES PATENT OFFICE

2,515,563

HOT LINE CLAMP

John L. McCullough, Independence, Calif.

Application January 13, 1947, Serial No. 721,757

1 Claim. (Cl. 173—273)

1

The present invention relates to new and useful improvements in clamps for high voltage power lines or conductors and the invention has for its primary object to provide a clamping device adapted for attaching to the usual insulator attached to the pole of a power line, the clamp being adapted for releasably securing the line in position on the pole.

An important object of the present invention is to provide a hot line clamp of this character adapted for detachable engagement with the insulator so that the insulator may be removed and replaced when the same becomes damaged or broken without necessitating an interruption in the line.

A still further object is to provide a hot line clamp of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a front elevational view.

Figure 3 is a top plan view.

Figure 4 is a vertical sectional view taken substantially on a line 4—4 of Figure 3, and

Figure 5 is a fragmentary sectional view taken substantially on a line 5—5 of Figure 4.

Referring now to the drawings in detail, wherein for the purpose of illustration I have disclosed a preferred embodiment of the invention, the numeral 5 designates a casting which forms the base of the clamp, the casting having a threaded recess 6 in its bottom portion adapted for mounting on the usual upstanding pin of a power line insulator of conventional construction (not shown). However, if desired, the bottom of the casting may be cemented or otherwise detachably secured to the insulator.

The top of the casting is formed with a pair of spaced parallel upstanding flanges 7 forming a channel 8 extending transversely of the casting.

The flanges 7 are formed with aligned notches 9 tapering toward the base of the channel 8, the base of the notches forming a groove 10 extending transversely of the groove 8 and in which the power line or conductor is adapted to seat.

Lips 11 extend outwardly from the opposite side of the casting 5 adjacent the ends of the

2

groove 10, the upper surface of the lip being curved as at 12 to form a continuation of the groove 10, the outer edge of the lips being rounded to avoid any sharp contacting edge with the cable or line seated in the groove.

A pin 13 extends between the flanges 7 at the rear edges thereof and on which is pivotally mounted a clamping head 14 having a groove 15 formed in its lower surface adapted for receiving the upper surface of the line or cable seated in the groove 10 when the clamping head is lowered into its clamping position.

The clamping head 14 is formed with a flat rear edge 16 adapted to rest upon the rear portion of the groove 8 to support the clamping head in an upwardly inclined position as shown in Figure 4 of the drawings to permit insertion of the line or cable in the groove 10. The clamping head is positioned between the flanges 7 and a screw 17 is threaded at an inclined angle in the bottom portion of the head and projects outwardly therefrom, the outer end of the screw having a flange 18 and an eye or ring 19 formed thereon.

The front edge of the base or casting 5 is formed with a shoulder 20 having a vertical slot 21 therein in alignment with the groove 8 and adapted to receive the screw 17 when the head 14 is moved into its lower position whereby the flange 18 will be engaged under the shoulder 20 in a line clamping position as shown in Figure 1.

In using the clamp the base 5 is first attached to the insulator after the latter has been mounted on the pole and the line or cable is then placed in the groove 10 and the clamping head 14 lowered into clamping position with the flange 18 engaged under the shoulder 20.

Should the insulator become damaged or broken, a suitable hot line tool engages the ring 19 to loosen the clamping head and the head 14 is then swung upwardly into its raised position as shown in Figure 4 so that the line may be removed from the groove 10, the clamp removed from the insulator, the insulator removed from the pole and replaced. The clamp is then re-placed in position in the same manner and the head 14 lowered into its clamping engagement.

It is believed that the details of construction and manner of use of the device will be readily understood from the foregoing without further detailed explanation.

Having described the invention, what is claimed as new is:

A hot line clamp comprising a base having a threaded aperture therein for attaching to an insulator of a power line pole, said base having a

groove in its upper surface, a clamping head pivoted at one edge to the base and adapted to enter the groove, said base and said head having complementary grooves in their opposed faces disposed transversely of the first-named groove, and adapted to receive the line therein, said base having a vertical slot in its edge opposite from the pivoted edge of the head, a shoulder in the side of the base under said slot, and a retaining bolt threaded in the head and adapted to enter the slot of the base, and said bolt having a head engaging said base under said shoulder.

JOHN L. McCULLOUGH.
